UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 21,912, dated October 25, 1892.

Application filed September 29, 1892. Serial No. 447,333. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

The leading feature of my design consists of a series of irregular-shaped ornaments or scrolls in the roccoco style, forming irregular disconnected panels, with sprays or branches of leaves and flowers of the rose running from

different parts of said ornaments, as represented in the accompanying drawing.

The design is printed in any desired color or colors or in bronze on tinted paper of any desired color.

What I claim is—

The design for wall-paper herein shown and described.

Witness my hand this 24th day of September, 1892.

CHARLES BOOZE.
